APPARATUS FOR STRINGING TOBACCO LEAVES

Arthur E. Palmer, Hartford, Conn., assignor to
 Wurton Machine Company, Philadelphia, Pa.,
 a corporation of Pennsylvania

Application April 22, 1948, Serial No. 22,596

1 Claim. (Cl. 214—5.5)

1

This invention relates to an apparatus for stringing tobacco leaves.

As is well known, when tobacco is harvested, the leaves are strung on lengths of string secured at one end to a lath, the free end of the string is attached to the other end of the lath and the whole then racked up in a curing barn with the leaves hanging from the string for the curing of the tobacco leaves.

When the tobacco has cured, the laths are taken down, the ends of the string are cut free from the lath, the tobacco leaves pushed together and the balance of the string wound about the butt portions of the leaves and secured to form hands.

In practice heretofore, the stringing of the pairs of tobacco leaves has been accomplished manually by operators who assemble the leaves and string them by passing a needle, carried by the string at its free end, through the butts of the leaves. Such is open to a number of objections, chief among which is variation in the number of pairs of leaves per lath, unequal spacing of the leaves on the string, wide variation in the number of laths strung per day by different operators, which results in a limited average production, breakage of leaves due to inept operators, loss from falling leaves during curing resultant from improper stringing, difficulty in obtaining requisite labor for a short seasonable occupation and rising labor costs coupled with decreasing productivity.

As a consequence, there have heretofore been many efforts made to provide mechanism and procedure for the mechanical stringing of tobacco leaves which would give a constant number of pairs of leaves per lath, equal spacing of the pairs on the string and increased productivity per operator. Such efforts in the main have been directed toward the provision of mechanisms including a needle and adapted to accomplish the same type of stringing which is accomplished by manual operation. However, the results of such and other efforts have failed, for various reasons, in their purpose and the procedure involving manual stringing of the tobacco leaves has been continued despite its several well recognized disadvantages.

Now in accordance with this invention, a mechanism for the stringing of tobacco leaves is provided which is at once economical and efficient in operation, in that uniform spacing and number of leaves per lath is readily obtainable, the leaves are securely held by the string, with mini-

2

mization of falling leaves, and the productivity of the operator is increased.

Generally speaking, the method according to this invention comprises the securing of leaves of tobacco at spaced intervals between a pair of strings, ends of which are secured together to an end of a lath, by successively twisting the strings together, or twisting one string about the other between tobacco leaves, the butts of which are successively presented between the strings. More particularly the strings are so arranged and manipulated that portions thereof will extend apart at rest in the form of a V for a period between each successive twisting operation, allowing the insertion between the strings of the butts of tobacco leaves and their engagement between the strings at the apex of the V form. The successive twistings of the strings secures the leaves thereto. It is to be noted that the strings are held under tension and when twisted tightly grip the butts of the leaves.

The apparatus according to this invention, generally speaking, will comprise intermittent rotary string carrying means for effecting twisting of the strings and causing the strings to be at rest for a period between twists in V form extension for the insertion and temporary holding of the butt portions of tobacco leaves.

In greater detail the apparatus will include 30 lath carrying means so arranged as to permit changing laths without stopping the apparatus.

Having now indicated, in a general way, the nature and purpose of this invention, I will proceed, with reference to the accompanying drawings, to a detailed description of a form of apparatus according to this invention and the operation thereof, from all of which the method according to this invention will be made apparent.

In the drawings:

40 Figure 1 is a side view of a tobacco leaf stringing machine embodying this invention.

Figure 2 is a side view, partly in section, of intermittent drive means included in the machine shown in Figure 1.

45 Figure 3 is a side view of string carrying means included in the machine shown in Figure 1.

Figure 4 is a rear view, partly in section, of the subject of Figure 3.

Figure 5 is a top view of the subject of Figure 1.

Figure 6 is a plan view showing a series of strung leaves and illustrating the stringing operation.

In the several views variously, 1 indicates a frame structure by which the various elements 55 comprising the machine are supported.

Mounted on the frame 1 is a shaft 2 upon which is mounted a pulley 3 adapted to be driven by a motor 4 through a belt 5. The motor 4 is provided with a stepped pulley 6 to enable the speed of the pulley 3 to be varied. The pulley 3 is connected to the shaft 2 by means of a coil spring 7, one end of which is connected to a collar 8 secured to the shaft by a pin 9 and the other end of which is secured to a collar 10 secured to the face of pulley 3. Mounted on the hub of pulley 3 is a cam 11 and a sprocket 12, while a disc 13 is mounted on the end of shaft 2.

Mounted on the rear face of disc 13 are a pair of spool holders arranged 180° apart and each comprising a bracket 14 and a spindle 15 adapted to receive lengths, for example, a spool, of string 16. The disc 13 is provided with holes 17, arranged 180° apart and 90° from the spindle 15, for the passage of string from the spools 15, guides 18 being provided for the string 16 from the spools. Adjacent to the holes 17 are adjustable spring tension devices 19.

A brake 20, carried by a lever 21 pivoted to frame 1 at 25 is normally held adjacent to, but clear of, the edge of disc 13 by means of an adjustable spring 22. The cam 11 acts on a rod 23 having a slot and pin connection 24 with frame 1 and having its lower end in contact with lever 21 to effect engagement of the brake 20 with the edge of disc 13 against the action of spring 22, as shown in Figure 1.

The cam 11 is set with respect to the spools of cord 16 on disc 13 so that the brake will be applied in each revolution of disc 13 (to stop the disc for a period) when the disc 13 is in such position that the cords 16 will extend therefrom in substantially a horizontal plane, as, for example, shown in Figure 5.

The sprocket 12 on the hub of pulley 3 is connected by means of a chain 26 to a sprocket 27 on a shaft 28, mounted on the frame 1. The shaft 28 carries at its end a pinion 29 in mesh with a gear 30 on a transverse shaft 31, which also carries a pulley 32 connected to a pulley 33 on a shaft 34 by a belt 35. The shaft 34 carries a sprocket 36 connected with a sprocket 37 on a shaft 38 by a chain 39. The chain 39 carries a pair of hooks 40 secured to the chain in spaced relation.

For the operation of the machine described above, the chain 39 is adjusted so that one of the hooks 40 will be just forward of the sprocket 36. Strings 16 from the lengths or spools on disc 13 are then drawn out, through holes 17 on disc 13, under tension and secured to the end of a lath A, as by wrapping their ends together about the end portion of the lath and passing through a slot in the end of the lath. The strings are then hung over the hook 40. Two piles of tobacco leaves B, the leaves of the piles extending in opposite directions with the butts adjacent, are placed upon a suitable support, as a table 41, in position adjacent to the disc 13, as shown, for example, in Figure 1.

The motor 4 is now started. As will be appreciated from the above description, while the motor acts to drive pulley 3 continuously and likewise, through chain 26, shaft 28, gearing 29-30 and belt 35, to drive the chain 39 continuously, it operates to drive shaft 2 and disc 13 through spring 7. During a part of each revolution of the pulley 3, the cam 11 will, through engagement with rod 23, apply the brake 20 to the edge of disc 13 holding it against turning and permitting the continued revolution of

the pulley to tension spring 7. When spring 7 has been tensioned, the brake 20 will be released by the passing of the cam 11 away from rod 23 and the spring 7 will then act to rapidly rotate disc 13 through one revolution. Thus, in each revolution of the pulley 3 the disc 13 will be held from turning for a period, the spring 7 will be placed under tension and disc 13 will then be revolved by spring 7, thus twice reversing the position of the spools and effecting a twisting of the strings 16.

The parts, including the spring 7, the cam 11 and the brake 20, will be so timed that in each revolution of disc 13 it will be stopped and the disc will be held from turning by the brake 20 with the strings 16 in substantially a horizontal plane, as shown, for example, in Figure 5, in which position the strings will remain until spring 7 is tensioned, then, with the release of brake 20, the disc 13 will be rapidly rotated by the spring 7 to effect a twisting of the strings 16, after which it will be again stopped by brake 20 and the action repeated.

With the machine in operation, the operator grasps a tobacco leaf from each of the piles on the table 41, and placing their butts together, inserts the butts between the strings 16, when the strings are at rest in a substantially horizontal position, on the stopping of the disc 13 by the brake 20. The butts of the pair of leaves are inserted by the operator between the strings 16 with an upward movement and then moved laterally into the V formed by the convergence of the strings to their point of last twisting. The strings being under tension, when the butts of the pair of leaves have been moved into the V formed by the convergence of the strings, they will be temporarily held until, on the release of brake 20, the strings are twisted by the rotation of the disc under the influence of spring 7.

The successive twists of the strings 16, which, it will be noted, are under tension, will securely hold the successive pairs of leaves. The insertion of the pairs of leaves between the strings 16, their movement into the V at the point of convergence of the strings for their temporary holding and the securing of the pairs by twisting of the strings is illustrated by Figure 6.

Pairs of leaves are successively inserted between the strings 16 as the disc is successively stopped and held by the brake 20 after successive twisting of the strings in each revolution of disc 20 until the proper number of pairs of leaves, usually 20 pairs, desired to be strung on a lath, have been strung.

When the requisite number of pairs of leaves has been secured by the twisting of the strings, the operator grasps the strings 16 beyond the last pair of leaves and, drawing some slack, severs the strings by any convenient means, as, for example, a fixed blade conveniently located, and while maintaining tension on the strings about the pairs of leaves, secures the severed ends of the strings to the free end of the lath A, as by winding around the end portion of the lath and passing through a slot in the end. The lath with its strung leaves is then removed from the hook 40 and racked up in the usual manner for curing the leaves. The ends of the strings extending from the disc are then secured to a fresh lath, which is laid over the succeeding hook 40 on chain 39 and the procedure of stringing as described above repeated, the strung laths being removed and fresh laths

being applied successively until the tobacco leaves to be strung are exhausted.

It will be appreciated that the operation of the machine will be continuous, the hooks 40 being so placed and the machine being operated at such a rate of speed as to permit the removal of strung laths and the application of fresh laths. It will be noted that in each revolution of the disc 13, the disc will be at rest for a period with the strings 16 in substantially a horizontal plane, during such period in each revolution the butts of a pair of tobacco leaves will be inserted between the strings and the pairs so inserted successively will be secured by the twisting of the strings in the rotation of disc 13 under the influence of spring 7.

When the tobacco strung as described above has been cured, the pairs of cured leaves may be readily removed from the lath by laying the lath and leaves flat on a table, severing the strings from the lath, and also desirably at intervals between their ends, bringing the leaves together and securing them in a bunch by winding the strings about their butts, it being noted that when the strings are severed the leaves may be easily brought together, since the strings being then slack, the twists will not form any obstruction. If desired, after the strings are severed one of the strings may be pulled out and the remaining string used to bind the leaves 30 into a bunch.

In the above description of apparatus and procedure reference is made to the stringing of tobacco leaves in pairs. However, it will be understood that such is intended to be illustrative and not limiting, it being apparent that single leaves, or groups, or bunches comprising more than two leaves may be strung as may be desired.

It will be appreciated that the specific apparatus described above as an illustrative embodiment of this invention from the apparatus standpoint and the description of the procedure for stringing tobacco leaves according to this in-

vention from the method standpoint, may be varied in detail without departing from the scope of this invention as defined in the appended claim.

The method disclosed has not been claimed herein, since such forms the subject-matter of an application filed by me as a division hereof, Serial No. 186,890, filed September 26, 1950.

What I claim and desire to protect by Letters Patent is:

Apparatus for stringing tobacco leaves comprising a shaft, drive means adapted to rotate continuously in one direction, a pair of spaced spools each carrying a length of string, a support secured to said shaft and carrying said spools, a coil spring secured at one end to said shaft and having its other end connected to said drive means, a brake operable on said support, cam means carried by said shaft for operating the brake, said cam means being arranged to effect operation of said brake means to stop said support at 360° intervals in the revolution of said shaft and to release said brake means when the coil spring has been substantially tensioned, means for advancing the free ends of said strings away from said support and frictional means on said support engaging said strings to resist said advancing of the strings.

ARTHUR E. PALMER.
